UNITED STATES PATENT OFFICE.

HORACE C. MOYER, OF OAK PARK, ILLINOIS, ASSIGNOR TO THE WINDSOR FURNITURE COMPANY, OF CHICAGO, ILLINOIS, A CORPORATION OF ILLINOIS.

GRAPHOPHONE.

1,279,743.

Specification of Letters Patent. Patented Sept. 24, 1918.

Application filed August 11, 1915. Serial No. 44,877.

To all whom it may concern:

Be it known that I, HORACE C. MOYER, a resident of Oak Park, in the county of Cook and State of Illinois, have invented certain new and useful Improvements in Graphophones, of which the following is a full, clear, and exact description.

The invention relates to graphophones.

In graphophones in which the horn is disposed in a case or cabinet, it has heretofore been the practice to provide a cabinet with superposed compartments, in the upper of which the instrument is disposed and in the lower of which the disks or records are stored. In these cabinets, as a result of the vertical arrangement of these compartments, the top of the machine was necessarily so high that it was not conveniently accessible for placement and removal of the records, and it was necessary for a person to stoop in removing the record from the lower compartment for placement on the instrument in the upper portion of the case. This movement of the body, necessary in shifting the disks from the instrument to the storage compartment or vice versa, was inconvenient and resulted, unless extreme care was used, in marring the record disks. Another disadvantage was that the disks could not be conveniently stored so they would be individually and collectively accessible.

One object of the invention is to overcome these objections inherent in graphophones now in general use.

In attaining this object of the invention, the instrument and the rack for holding the records are disposed in compartments arranged side by side in a cabinet mounted upon legs to bring the upper portion of the cabinet at the correct elevation for convenient access to the instrument and handling of the disks, and having a cover extending over both compartments to render the instrument and records simultaneously accessible.

A further object of the invention is to provide an improved combined graphophone and record cabinet.

The invention consists in the several novel features hereinafter set forth and more particularly defined by claim at the conclusion hereof.

In the drawings:

Figure 1 is a vertical longitudinal section of a graphophone embodying the in-

vention. Fig. 2 is a section taken on line 2-2 of Fig. 1. Fig. 3 is a plan the lid being shown in the open and in section. Fig. 4 is a horizontal section taken on line 4-4 of Fig. 1.

The body of the cabinet comprises a fixed bottom 7, usually formed of wood and mounted upon legs 8, fixed side walls 9 and 10, a back 11, a front 12, and fixed upright members or corner posts 18 which may be integral with the legs. A fixed bar 21 extends across both compartments adjacent the top and front of the body. At the rear, a fixed top-bar 22 extends between the rear posts 18. A transverse partition 14 is fixed in the body and divides the latter into a chamber 15 at one side thereof adapted to contain the talking machine 16 and a compartment 17 at the other side thereof adapted to contain a rack for the record disks.

Compartment 17 has a fixed wall 19 and a fixed rear wall 20. A transverse bottom-bar 23 is fixed to walls 19 and 20 and is disposed above the bottom 7 to hold the disks elevated. Vertically grooved strips 24 and 25 are secured to side 9 and partition 14, respectively, and longitudinal division strips 26 are slidably held in vertical grooves formed in strips 24 and 25 to form a rack in compartment 17 adapted to hold a large number of disks in vertical position and so that the upper portions of the disks will be in separated relation. Stops 27 are secured to strips 24 and 25 to hold the dividing strips 26 in grooves 28. It will be observed that when the disks are held in the rack, as indicated by dotted lines in Fig. 1, the upper portions thereof will be separated and accessible, so that each disk can be conveniently handled.

A lid 30 is hinged to bar 22, as at 31, has side strips 32 and a front strip 33 adapted to rest on the top of the body, and forms a cover for all of the contents of the cabinet. By forming these strips on the lid, the upper portions of the disks in compartment 17 and the sound box of the instrument 16 will be conveniently and accessibly disposed at the top of the body of the cabinet when the lid is open.

The frame 35 of the instrument 16 is removably mounted upon a bracket 37 secured to partition 14, and a bracket 38 secured to the side wall 10 and front bar 21. The motor 39 for the machine may be of

60

75

95

100

105

110

usual construction and is secured to the machine frame 35 and the disk-carrier 40 is mounted to rotate above the frame 35. The sound-box 42 is connected to a horn 43 which 5 is secured to a vertical shaft 44 which is mounted in a step bearing 45 on the bottom 7 and a bearing 47 of bracket 38. This pivotal mount for the horn and sound-box permits the needle on the latter to move 10 responsive to the record on the disk. A crank 46 extends through the side-wall 9 and may be connected to the motor 39 in manner well understood in the art.

The front of compartment 15 is open for 15 the escape of sound from the horn. A frame 48, on which network of ratan or other suitable material is secured, is provided with tongues 50 which are slidably held in vertical grooves 51 in the front uprights 18 of the cabinet, to permit the sound to escape from compartment 15 and to serve as a guard for the front of the compartment. The frame 48 is extended across the entire front of the cabinet. The tongues 20 50 and grooves 51 extend to the upper ends of posts 18, so that when the lid 30 has been lifted, the frame can be lifted out of the grooves to give convenient access to the instrument in the chamber 15 whenever repair 25 or lubrication of the instrument becomes necessary. An angular strip 60 rests upon bracket 37 and a stop 61, to close the space between the frame 35 and partition 14 and the front of compartment 15. This strip is 30 removable to provide access to the side of the frame. The space at the other side of the frame 35 is closed by an angular strip 63 which rests upon bracket 38. These angular strips rest upon their supports and 35 can be readily removed when access to the frame 35 is desired.

The back 11 of the cabinet is provided with tongues 11^a, fitting in grooves 18^a and 18^b formed in the rear uprights 18, respectively. This back wall fits between the bottom 7 and bar 22 and is formed so that by moving it endwise a short distance to withdraw the tongue 11^a from groove 18^a, it may be swung rearwardly sufficiently to clear the 40 post in which the groove is formed and then withdrawn longitudinally from the

groove 18^b. This back is removable to provide access to the rear of the compartment 15.

The invention thus exemplifies an improved graphophone, in which the sound instrument and the rack for the record disks are disposed side by side in a cabinet. As a result of this construction, when the lid 30 is lifted, a record may be transferred with 55 facility from the rack to the rotatable carrier 40 of the instrument and vice versa, and this transfer may be made with facility and without danger of marring the records. The records are disposed where they are 60 conveniently accessible for individual handling and in close relation to the instrument and provision is made for inspection and access to substantially all portions of the instrument when repair or inspection become 65 necessary. In practice, the height of the lid is about the same as an ordinary table, and when the instrument is not in use, the lid may be utilized as a table or support, and as a result of its being extended over both 70 compartments, its area is sufficient for that purpose.

The invention is not to be understood as restricted to the details set forth, since these may be modified within the scope of the 80 appended claim, without departing from the spirit and scope of the invention.

Having thus described the invention, what I claim as new and desire to secure by Letters Patent, is:

A graphophone cabinet comprising the combination of a body having an open top, means to support a sound reproducing instrument in the body and adjacent the top and at one side thereof and a horn in the 90 body and at the same side and below the instrument, means to removably hold record disks in and at the other side of said body and laterally adjacent to the instrument, and means to close the top of said body, adapted 95 to extend over the instrument and disks and operable to render the instrument and disks simultaneously accessible.

HORACE C. MOYER.
